GRINDER WHEEL DRESSER

Jerome H. Newman, 13971 Skyline Blvd., Oakland, Calif.

Filed Nov. 2, 1959, Ser. No. 58,168

Term of patent 14 years

(Cl. D37—1)

FIGURE 1 is a top plan view of a grinder wheel dresser, showing my new design;

FIGURE 2 is a right side elevational view thereof;

FIGURE 3 is a rear elevational view thereof;

FIGURE 4 is a front elevational view thereof;

FIGURE 5 is a bottom plan view thereof; and

FIGURE 6 is a left side elevational view thereof.

The dominant features of my design reside in the portions shown in full lines.

I claim:

The ornamental design for a grinder wheel dresser, substantially as shown and described.
